UNITED STATES PATENT OFFICE.

JOHN J. KUTSCHEID AND JOSEPH J. KUTSCHEID, OF CHICAGO, ILLINOIS.

TREADLE MECHANISM FOR SHEARS.

1,146,175.

Specification of Letters Patent. Patented July 13, 1915.

Application filed January 24, 1914. Serial No. 814,137.

To all whom it may concern:

Be it known that we, JOHN J. KUTSCHEID and JOSEPH J. KUTSCHEID, citizens of the United States, and residents of the city of Chicago, county of Cook, and State of Illinois, have invented certain new and useful Improvements in Treadle Mechanism for Shears, of which the following is a specification.

Our invention relates to metal shears and has for its object the production of a machine of this character which will be of improved construction and efficient in operation.

Other objects will appear hereinafter.

The invention consists in the combinations and arrangements of parts hereinafter described and claimed.

The invention will be best understood by reference to the accompanying drawing forming a part of this specification, and in which—

Figure 1 is a vertical transverse section of a metal shears embodying our invention, Fig. 2 is a top plan view of the treadle of the machine detached, Fig. 3 is a fragmentary sectional detail illustrating the connection of the treadle with the bar which connects with the relatively movable blade of the device, and Fig. 4 is an enlarged detail section taken on substantially line $x-x$ of Fig. 2.

The preferred form of construction as illustrated in the drawing comprises a supporting frame consisting of four legs 1 which preferably diverge toward their lower ends as shown. The upper ends of the legs 1 at the same side of the machine are rigidly connected to a channel frame 2. Rigidly secured to and extending between the channel members 2 is the bed of the machine consisting of an elongated channel member 3 open at its upper side and a plate 4 which is fitted in said side of said body as shown. The body 3 is secured at its ends rigidly to the end members 2 and the same also rests upon the upper ends of legs 1, resulting in a construction possessing great firmness and rigidity. In order to permit of the seating of the plate 4 in the upper side of body 3 as mentioned the upper edge of the latter is countersunk or stepped and the periphery of said plate is correspondingly formed, as clearly shown in Fig. 1.

Arranged adjacent the rearward longitudinal edge of the bed plate 4 is the relatively

stationary blade of the device which is secured to the rearward wall or portion of the body 3 by means of bolts 6. The bolts 6 pass through vertically extending elongated slots provided in said portion of the body 3 so as to permit of slight vertical adjustment of blade 5 as will be readily understood. Said blade is held in positions of adjustment by means of screws 7 which are threaded in a reinforcing T-bar 8 rigidly secured as by riveting to the under side of body 3 at the rearward edge thereof. The screws 7 engage against the under edge of blade 5, and serve to support the same, limiting downward movement thereof as is apparent.

Arranged in operative proximity with the blade 5 is a relatively movable blade 9 which is detachably secured to an elongated transversely extending carrier or holder 10 the ends of which are slidably mounted in vertically extending channels 11 provided at the inner sides of the frame members 2. A helical tension spring 12 co-operates with each end of the carrier 10 to normally hold the blade 9 in elevated position as shown.

Vertical reciprocation or actuation of blade 9 is effected by means of a treadle arranged at the base of the machine, said treadle being connected therewith by means of rods 13 provided at the respective ends or sides of said treadle, and which bars are connected at their upper ends with depending extensions or arms 13' which are connected with carrier 10. Said treadle comprises a rectangular peripheral frame 14 formed of angle iron, the rearward edge of which is rockingly or pivotally mounted upon a bar 15 which is supported at its ends in the legs 1 at the rearward side of the machine. Co-operating with the treadle frame 14 are elongated truss bars 16 arranged in pairs obliquely of said frame, the ends of bars 16 being secured to said frame at the corners thereof, one bar of each pair being arranged above the inwardly extending flange of frame 14 and the other below said flange as clearly shown in Fig. 1. The central portions of said bars at their points of intersection are spaced apart by means of a transversely or perpendicularly extending bolt 17 and nuts 18 threaded upon said bolt which engage against the inner sides of said bars as clearly shown in Fig. 4. Said bolt and nuts serve to hold the central portions of bars 16 spaced apart a greater distance than the ends thereof, whereby a

sort of truss is constituted connecting the diametrically opposite corners of the treadle frame. Through this arrangement it will be seen that pressure applied to any portion 5 or to any point of the frame 14 will be equally distributed, so as to insure both bars 13 being correspondingly actuated and hence both ends of blade carrier 10 correspondingly moved. In other words the provision 10 of the truss bars 16 renders the frame 14 so rigid as to obviate the possibility of sagging of any corner or of warping of said frame. With this arrangement in the event of pressure being applied to the free edge 15 of frame 14 at one end thereof, this pressure will be transmitted through the adjacent bars 16 to the opposite side of said frame in order to equalize or uniformly distribute said pressure and so that just as effectual 20 rocking of said treadle may be secured by engaging either end of the free edge thereof as the central part of said edge. Without the provision of the bars 16, in the event of pressure being applied to the forward bar 25 of the frame 14 adjacent one end thereof, this end would be moved downwardly a greater distance than the opposite side, which would lag behind, the result being that the bars 13 would not be moved uniformly 30 and thereby effect binding of the blade carrier 10 in guides 11.

Through the counter-sunk arrangement of bed plate 4 as shown and described a bed possessing great strength and rigidity is 35 effected, the sides of the bed body 3 by reason of this arrangement serving to engage with the periphery of said plate so as to relieve the strain upon the securing bolts or other fastenings of said plate. Also, with 40 this arrangement, said plate serves to reinforce the walls of said bed body, especially the rear wall thereof carrying the blade 5, any outward pressure to which said wall is subjected, when the machine is in use, being 45 transferred through the plate 4 to the outer wall of said bed body as will be readily understood.

While we have illustrated and described the preferred form of construction for carrying our invention into effect, this is capable of variation and modification without departing from the spirit of the invention. We, therefore, do not wish to be limited to the precise details of construction set forth, 50 but desire to avail ourselves of such variations and modifications as come within the scope of the appended claims.

Having described our invention what we claim as new and desire to secure by Letters Patent is:

1. In mechanism of the class described, the combination of a movable member; a treadle for operating said movable member, said treadle comprising a rockingly mounted substantially rectangular peripheral frame; 60 a connection between said frame and said member whereby, upon rocking of said frame, said member will be actuated; and a pair of obliquely disposed reinforcing bars connected with said frame at the corners 65 of the latter, the central portions of said bars being spaced apart at a distance greater than the ends of said bars, substantially as described.

2. In mechanism of the class described, 70 the combination of a movable member; a treadle for operating said movable member, said treadle comprising a rockingly mounted substantially rectangular peripheral frame; a connection between said frame and said 75 movable member whereby, upon rocking of said frame, said member will be actuated; pairs of obliquely disposed reinforcing bars connected with said frame at opposite sides 80 at the corners thereof; and adjustable means 85 at the central portions of said bars spacing said central bar portions apart a distance greater than the ends of said bars, substantially as described.

3. In mechanism of the class described, 90 the combination of a movable member; a treadle for operating said movable member, said treadle comprising a rockingly mounted substantially rectangular peripheral frame; a connection between said frame and said 95 member whereby, upon rocking of said frame, said member will be actuated; pairs of obliquely disposed reinforcing bars connected with said frame at opposite sides at the corners thereof; and a transversely ex- 100 tends bolt and nuts threaded on said bolt arranged at the central portions of said bars for spacing said central portions apart a distance greater than the ends of said bars, substantially as described.

In testimony whereof we have signed our names to this specification in the presence of two subscribing witnesses.

JOHN J. KUTSCHEID.
JOSEPH J. KUTSCHEID.
